UNITED STATES PATENT OFFICE.

THOMAS J. MORRIS, OF SPRINGFIELD, MASSACHUSETTS.

DESIGN FOR A PIPE-HANGER.

46,687.

Specification for Design.

Patented Nov. 24, 1914.

Application filed April 13, 1914. Serial No. 831,642. Term of patent 14 years.

To all whom it may concern:

Be it known that I, THOMAS J. MORRIS, a citizen of the United States, residing at Springfield, in the county of Hampden and State of Massachusetts, have invented a new, original, and ornamental Design for a Pipe-Hanger, of which the following is a specification, reference being had to the accompanying drawing, forming part thereof.

In the drawings:—Figure 1 is a front

view; Fig. 2 is an edge view; and Fig. 3 is a plan view.

I claim:—

The ornamental design for a pipe hanger, as shown.

THOMAS J. MORRIS.
